John C. Schrader.

UNITED STATES PATENT OFFICE.

JOHN C. SCHRADER, OF WARWICK, RHODE ISLAND.

EXPLoder FOR BLASTING-CARTRIDGES.

SPECIFICATION forming part of Letters Patent No. 253,893, dated February 21, 1882.

Application filed August 11, 1881. (No model.)

To all whom it may concern:

Be it known that I, JOHN C. SCHRADER, of Warwick, in the county of Kent and State of Rhode Island, have invented a new and useful Improvement in Cartridge-Exploders; and I do hereby declare that the following specification, taken in connection with the accompanying drawings, forming a part of the same, is a full, clear, and exact description thereof.

My exploder is especially intended for use in blasting in coal and other mines, but is adapted and will be useful for exploding cartridges for other purposes. I make use of the tubular blasting-bar heretofore commonly used in blasting in coal-mines in place of a safety-fuse, which is comparatively expensive. This tubular blasting bar extends the entire length of the hole which has been drilled in the material to be blasted, and which in coal-mining is usually not less than six feet in depth. Heretofore it has been customary to simply insert the lower end of this tubular blasting-bar into the neck of a cartridge of powder and tie the neck of the cartridge firmly around the blasting-bar.

The blasting-bar and cartridge having been placed in the drilled hole and the hole having been properly tamped with pieces of coal, dry sand, or other suitable material, a squib composed of a straw filled with powder, or of other well-known construction, was inserted into the external end of the tubular blasting-bar and lighted. This squib, by the force of the powder contained therein, was caused to dart along the length of the blasting bar or tube, and, while still ignited, to come in contact with, ignite, and explode the mass of powder in the cartridge. With this means for exploding the cartridge the powder in the cartridge would at first be ignited only at that end of the mass with which the lighted squib first comes in contact, and the fire thus started has to travel the length of the mass of powder before it is all ignited. To obtain the best results in blasting with powder it is necessary that the entire mass should be exploded as simultaneously as possible. To accomplish this I employ a cap of fulminating mercury or other suitable fulminate to explode the mass of powder, which fulminate, upon being exploded, shoots a volume of fire into the mass of powder and ignites instantly a much larger quantity than can be ignited by a squib or a fuse.

Attempts have hitherto been made to use a fulminating-cap in connection with a blasting bar or tube and a squib to explode a cartridge of powder; but in all such attempts the cap has been so inserted in the lower end of the tubular blasting-bar that the fulminate contained in the cap has come within the blasting bar or tube. This has been attended with two serious difficulties: First, the explosion of the fulminate in this position was almost certain to rend or split the blasting-bar, which, when reduced below a certain length, becomes useless for the purpose required; and, secondly, when if for any reason the squib should fail to explode the fulminate it becomes necessary, as it sometimes does, to clear the blasting bar or tube of any pieces of coal or other matter which might interfere with the passage of a new squib, there was great danger of causing a premature explosion of the cap and cartridge by reason of the liability of hitting or scraping the fulminate in the cap with the scraper or cleaner used for clearing the blasting-tube.

For the above reasons it has heretofore been also impracticable in coal and similar blasting to use, in connection with a blasting-tube and a squib, dynamite, nitro-glycerine, or any one of that class of higher explosives which require a fulminating-cap to explode them, although I have discovered by numerous experiments that this class of explosives—and especially those of a low degree—can be used to great advantage in blasting of this kind.

The object of my invention is to make practicable the use of a fulminating-cap in connection with a blasting-tube and a squib to explode a cartridge, and thus to make also practicable the adoption and employment of that class of higher explosives requiring the use of a fulminating-cap for their explosion; and my invention consists in so locating the cap containing the fulminate with reference to the blasting bar or tube that the entire quantity of the fulminate shall lie below the plane of the lower end of the blasting bar or tube; and it also consists in so constructing the metallic cap containing the fulminate, or so providing it with a protector, that while a channel is furnished for communicating fire from the squib to the fulminate, this channel is of such a nature or of such a construction that the fulminate is protected from being exploded

by percussion or friction, and the scraper or cleaner used for clearing the blasting-tube is prevented from reaching or coming in contact with or in any way causing to explode the fulminate contained in the cap.

Referring to the drawings, Figure 1 represents in longitudinal vertical section one form of device containing my invention, and Fig. 2 represents, likewise in longitudinal vertical section, another form of device for the same.

A in both figures represents the tubular blasting-bar, which is inserted in the neck of the cartridge B, which is filled with powder, dynamite, nitro-glycerine, or other explosive, 15 b, to be used, the neck of the cartridge being firmly tied to the blasting-bar by a string, as at a.

C is the cap containing a quantity of fulminating-mercury or other suitable fulminate, D, 20 which cap in the device represented at Fig. 2 is of about twice the length of that in Fig. 1, and is provided at its upper end with the flange c.

In the device shown in Fig. 1 the cap C is 25 provided with a protector, E, made of any suitable material—as wood, for instance—which protector E has a longitudinal bore, e e', through its entire length of sufficient diameter to receive the cap containing the fulminating-mercury or other fulminate. That portion of the bore e e' not occupied by the cap C is filled with powder, gun-cotton, or other easily inflammable material, as at b'. This bore is enlarged at its upper end to the 30 full size of the protector E, in order that if the squib should be diverted in its course from the center of the blasting bar or tube it may still come in contact with easily-inflammable matter, and over the top of the protector, when 35 powder is used to fill the bore, I usually place, to keep the powder from spilling, a diaphragm of paper, d, soaked with niter or other substance to render it readily inflammable. The longitudinal bore e e', and the powder, gun- 40 cotton, or other material contained therein, furnishes a channel or means of communication for the fire from the squib to reach the fulminate D, and the powder, gun cotton, or other inflammable matter thus placed above 45 the fulminate prevents the scraper from coming in contact therewith and protects it from being exploded by percussion or friction.

If desired, the protector E may be so constructed as of itself and apart from the powder 50 or gun-cotton contained therein to prevent the scraper from coming in contact with the fulminate. This may be accomplished, as shown in Fig. 1 of the drawings, by making the longitudinal bore e e' of two different diameters, 55 the lower portion, e, of said bore being of sufficient diameter to receive the cap containing the fulminate, and the upper portion, e', of said bore being of smaller diameter than the portion e, and of smaller diameter than the diameter of the scraper used for clearing the blasting-tube. With this construction (and it is the

one which I prefer to make use of) the size of the upper portion of the bore in the protector effectually prevents the entrance of the scraper and protects the fulminate from explosion by 70 percussion or friction. The protector E is attached to the lower end of the blasting bar or tube A by a short tube of parafined paper, F, or other suitable confection, into one end of which tube the protector E is inserted, and the 75 other end of which tube surrounds the lower end of the tubular blasting-bar, to which it is firmly tied by a string, as at a'.

In the device represented at Fig. 2 the cap C is provided with a quick fuse, G, composed 80 of any suitable combustible material which is sensitive enough to take fire from the least spark from the squib, but which cannot be ignited by percussion or friction. One end of this quick fuse G is inserted into the upper extended end of the cap C above and extending down to the fulminate D, and the other end of the fuse G enters the lower end of the blasting bar or tube A, the fuse G thus forming the connection between the cap and the blasting- 90 tube. The flange c upon the upper end of the cap C abuts against the lower end of the blasting-tube A, and prevents the cap from being in any way forced into the blasting bar or tube. The fuse G constitutes the channel or means 95 to communicate the fire from the squib to the fulminate D in the cap C, and at the same time prevents the scraper or cleaner from coming in contact with or exploding the fulminate, the fuse being insensitive to percussion or friction. 100

The operation of the device represented in Fig. 1 is as follows: The parts having been placed in position with reference to each other, as shown in the figure, and properly united, the device is inserted to the proper depth in 105 the hole that has been drilled in the material to be blasted. The hole is then tamped in the usual manner, and the squib, having been introduced into the upper end of the tubular blasting-bar A, is lighted. The force of the 110 powder in the squib carries it along the blasting bar or tube until it reaches the lower end of the tube. The lighted squib there comes in contact with the paper diaphragm d, if one is 115 used, or, if not, directly with the powder, gun-cotton, or other inflammable matter, b', and immediately ignites it. The flame is carried through the inflammable matter in the channel or bore e e' to the fulminate D and explodes 120 it, and the fulminate in turn forcibly explodes the cartridge D by means of the volume of flame which it shoots into the mass, if powder be employed, or by means of the percussion caused by the cap C, if the cartridge be one of dynamite, nitro-glycerine, or one of the higher explosives requiring a fulminating-cap to explode 125 it.

The operation of the device represented in Fig. 2 is similar to that of the device already described. The same preparatory steps having been taken, the squib, when it reaches the 130 lower end of the blasting-tube A, comes in con-

tact with the quick fuse G. This quick fuse is instantly ignited and immediately conveys the flame to the fulminate in the cap C and causes its explosion, and the fulminate in turn explodes the powder, dynamite, nitro-glycerine, or the explosive used in the cartridge B, as previously described.

In both of the illustrated embodiments of my invention the cap and the firing medium, with their inclosing-case, constitute a fulminate-exploder, and, as indicated herein by me, the firing medium by which the cap is exploded is a small quantity of loose powder, which is directly fired by a squib, as in Fig. 1, or indirectly fired by the squib through a short length of fuse within the firing-tube, as in Fig. 2. I am aware that fulminate-exploders of various kinds have heretofore been employed in combination with cartridges and arranged to be fired by means of safety-fuses, and also by electrical apparatus; but so far as I know I am the first to provide for firing fulminate-exploders by means of squibs, as by the firing tube or bar, and I have so combined the fulminate-exploder and cartridge with the firing-tube that the fulminate is protected from being fired by the percussion or friction incident to or liable in the use of clearing-tools within the firing-tube, as is frequently requisite in practical operations. While I have represented in the drawings and have described two specific devices for carrying my invention into effect, I do not mean to limit myself to the peculiar devices described, as it is evident that a variety of different ways may be devised for accomplishing the results specified which would embody the principles

of my invention—as, for instance, the cap containing the fulminate may be so constructed as by contracting its upper portion to prevent the admission of the scraper used for clearing the blasting-tube, and at the same time furnish a proper and sufficient channel for the transmission of the flame. It is obvious, too, that instead of providing a single channel or opening, several might be employed, as by furnishing the top of the extended cap with a perforated diaphragm which would arrest the scraper, but allow the communication of the flame to the powder or other inflammable matter contained in the cap.

What I do claim as my invention, and desire to secure by Letters Patent, is—

1. The combination, substantially as herein-before described, of the tubular blasting tube or bar, the cartridge connected therewith, and a fulminate-exploder connected with the blasting-tube, located within the cartridge and beyond the end of said tube, as and for the purposes specified.

2. The combination, substantially as herein-before described, of the tubular blasting tube or bar, the cartridge connected therewith, and a fulminate-exploder connected with the inner end of said tube within the cartridge and communicating with said tube for firing purposes by way of a passage or channel of lesser diameter than that of the blasting-bar, as and for the purposes specified.

JOHN C. SCHRADER.
